UNITED STATES PATENT OFFICE.

DIGHTON A. ROBINSON, OF SEATTLE, WASHINGTON.

TUNNELING-MACHINE.

1,146,281.

Specification of Letters Patent. Patented July 13, 1915.

Application filed September 3, 1908. Serial No. 451,512.

To all whom it may concern:

Be it known that I, DIGHTON A. ROBINSON, of Seattle, King county, Washington, have invented certain new and useful Improvements in Tunneling-Machines, of which the following is the specification.

My invention relates to machines for tunneling a rock formation and the object of the invention, is to provide a machine by means of which the heading can be easily and quickly drilled and channeled preparatory to the blasting operation.

A further object, is to provide a machine which will obviate the necessity of removing an immense amount of rock, which, during the blasting operation, would break outside the necessary lines of the tunnel. The cutting out of only so much rock as is necessary for the tunnel, saves the expense of filling unnecessary space and renders the work safer for the men, as the channeling operation will have the effect of keying the loose pieces of rock in the walls.

A further object, is to provide a machine, which after drilling and channeling, can be withdrawn from the heading and a receptacle substituted therefor, to receive the fragments of rock from the blast.

A further object is to provide a machine of simple construction, one which can be easily moved to and from the work and being composed of comparatively few parts, will be strong and durable and require but little attention in the way of repairs.

In carrying out my invention, I propose to provide a machine having a series of drills for putting the blast holes into the heading. Around these holes, a channel is cut in the rock to prevent the walls of the tunnel from being shattered when the heading is blasted. It is my purpose to provide recesses in the side walls of the tunnel capable of receiving the drilling and channeling mechanism to remove it from the force and effect of the explosion.

I have shown the drilling and channeling apparatus combined in one machine, but in practice, I propose to build them separately as I believe better results can be obtained through independent operation of these mechanisms. The drilling machine would be used first, and then withdrawn from the heading and switched into a recess provided therefor in the side wall of the tunnel. The channeling machine would then be moved forward and a channel cut in the heading

around the drilled holes. Then it would be withdrawn and switched into a recess similar to the one provided for the drilling machine. I would then move a car forward having a pan or receptacle thereon which when adjusted on the floor of the tunnel in front of the heading, is adapted to receive the fragments of rock from the blast. The pan would then be drawn up on to the platform of its car, and removed from the tunnel. The drilling machine would then be switched back on to the track, moved up to the heading and the operation repeated.

In the drawings, of this application, I have illustrated the drilling mechanism and channeling machine combined in one apparatus. It will be understood, however, that I do not confine myself to this construction, as I believe the independent construction and operation of these mechanisms to be more practicable.

In the accompanying drawings forming part of this specification, Figure 1, is a longitudinal sectional view of my improved tunneling machine, illustrating it in operation within a tunnel, Fig. 2, is a side elevation of the car whereon my tunneling apparatus is mounted, Fig. 3, is a transverse sectional view of the machine, Fig. 4, is a sectional view illustrating the manner of supporting the rotary channeling drum, Fig. 5 is a front elevation of the machine, showing the number and arrangement of the drills. Fig. 6 is a detail sectional view showing the means for mounting the feed wheel and holding it against displacement.

In the drawing, 2 represents a track laid upon the floor of the tunnel.

3 is a car adapted to travel back and forth on said track. At the top of the car, jack screws 4 are provided between the car and the top of the tunnel for the purpose of holding the car rigidly during the operation of the machine.

5 is a stationary tube supported horizontally in hubs 6 and 7 on the car 3 and projecting forwardly therefrom. Within the tube 5 and concentric therewith, I provide a stationary tube 8 supported in hubs 9, 10 and 11, and inclosing a revolving drill spindle 12 on the forward end of which a diamond drill 13 is mounted. A gear 14 has a hub 15 splined on the spindle 12, said gear meshing with a gear 16 on a shaft 17 which is driven through gears 18 and 19 from an electric motor 20. Accidental backward

- movement of the gear 14 is prevented by its engagement with the flange on the gear 16. A threaded rod 21 is connected to the inner end of the drill spindle 12, and has a sliding connection with a bracket 22 on the car frame and is provided with a wheel 23 having its hub in engagement with said bracket. The revolution of this wheel will feed the drill spindle forward or retract it as desired.
- 5 32" mounted on the car 3. The drill cylinders are constructed to impart a reciprocating movement to the drills. Mechanism may also be provided in the drill cylinders for regulating the feed of the drills and this 70 being of ordinary construction, I have omitted detail views, and make no claim to the same herein. There may be any desired number of the drills according to the size of the tunneling machine and when the drills 75 are withdrawn from the heading, the spider supporting them, may be revolved in either direction, so that the operator can reach any part of the heading in which it is desired to drill a hole.
- 10 80 Upon the tube 5, a series of grooved anti-friction rollers 36 are mounted extending at intervals around the tube and adapted to receive the V shaped inner edges of rings 37 and 38 which are secured to the inner surface of a drum 39. This drum is in the form of a truncated cone having its open larger end opposite the heading of the tunnel and within which end the frames supporting the drills project. This drum is arranged to revolve around its axis. Any suitable mechanism may be employed for imparting a revolving movement to the drum, but I have illustrated in the drawing, a simple apparatus by means of which this revolution may 85 90 be performed.
- 15 95 40 represents a ring having internal gear teeth and secured to the inner surface of the drum and meshing with a pinion 41 on a shaft 42. A worm wheel 43 is secured on 100 said shaft and meshes with a worm 44 on a shaft 45 which is transversely mounted on the car 3 and is provided with a gear 46 meshing with a pinion 46' on the shaft of a motor 47. Through this driving connection, 105 the drum is revolved at the desired speed.
- 20 110 Upon the periphery of the drum at suitable intervals, I arrange a second series of secondary drills which I prefer to designate as channelers, the revolving drum and the 110 drills carried thereby, comprising the channeling apparatus. These channelers will be connected with the revolving drum air tank. This apparatus is for the purpose of cutting a channel or groove in the heading around 115 the series of drill holes therein, so that when the heading is blasted the rock will be blown out without shattering or destroying the regular formation of the tunnel roof, and walls. A series of screws 48 are mounted at 120 intervals on the periphery of the drum and carry gears 49 which mesh with a stationary gear 50 that is secured to the tube 5. The engagement of the gear 49 carried by the revolving drum with the stationary gear 50, 125 will impart a revolving movement to the screw 48 and feed the drill carriage 50' forward to the work. A drill cylinder 51 is provided for each channeling drill 52 and is connected by links 53 with the carriage 50. 130

- 60
- 65

An adjusting wheel 54 is provided for the purpose of swinging the cylinder 51 on said links and drawing the channeler in toward the drum when it is retarded and increasing 5 the space between the channeler and the wall of the tunnel. If the blocks or supports for the drills were made solid, this would not be possible. A clutch device 55 is provided on the screw 48 by means of which the gear 10 49 may be rendered operative or inoperative.

It is sometimes desirable to withdraw one or more of the channeling drills from the heading without disturbing the others and I therefore provide a reversible motor 56 15 within the car having a flexible shaft 57 that is adapted to be temporarily attached to the end of the screw 48. When this attachment has been made, and the gear 49 rendered inoperative, the screw 48 may be 20 revolved and the drill carriage 50 rapidly withdrawn from or returned to its working position, the drum of course being temporarily stationary. The cylinders 51' will be 25 connected with the air compressor in the same manner as described with reference to the cylinders 32, except that suitable provision will be made to allow revolution of the drum without interfering with the tubes leading to the air tank.

30 In a machine of this type, in order that a flat floor may be formed in the tunnel, it is necessary to provide a mechanism for cutting out the triangular blocks at the bottom of the tunnel wall on each side of the center line, and to accomplish this without shattering 35 the tunnel wall, I provide vertically operating channeling drills supported on each side of the car. This mechanism I will now describe in detail.

40 58 is a carriage movable horizontally on guides 59 by a screw 60 that is supported in bars 61 mounted on brackets 62 which are hinged to the side walls of the car. These brackets are capable of swinging inwardly 45 against the car walls, but are normally held in a position at right angles thereto by means of brace bars 63. These brace bars are pivoted at one end to the car and are detachably connected by means of pins 64 to 50 the brackets 62. Upon the removal of these pins, the brackets and the vertically arranged drill carriages may be swung inwardly in an inoperative position. Drill cylinders 65 are mounted on the carriages 58 55 and support drills 66 having feed screws 67 geared to motors 68. The carriages 58 are moved back and forth on the screw shaft and the screws are revolved through cable connections 69 with the hub 15.

60 In the operation of this machine, the car is run forward into the tunnel, and the central socket formed in the heading. At the same time, a series of holes may be drilled in the heading around the central one any desired 65 distance apart and at a suitable angle.

A channel is cut in the heading around the drill holes by means of the revolving drum and the channeling drills carried thereby. The car is then withdrawn from the work and where two independent drilling and channeling machines are employed, they will be successively switched into recesses in the walls of the tunnel and a car moved forward carrying a receptacle or pan to receive the rock when the blast is made. The pan when loaded, is drawn back upon the car which is pulled out of the tunnel and the operation of drilling and channeling, may then be repeated. With this apparatus, I am able to drill and blast out a tunnel at very much 70 less expense than is ordinarily required for work of this kind, and a machine of this type and operating in this way, will have a larger capacity than any other apparatus heretofore employed for this purpose. 75

The car will be supported on a suitable number of wheels preferably eight, having solid bearings and the entire construction will be of steel. The revolving drum will preferably be made of steel plates with 80 plain butt joints traveling on the grooved rollers. When the inner tube or shaft has been inserted into the hole in the heading, the jack screws will be adjusted to lock the car rigidly. Various sizes and types of 85 drills may be employed according to the character of the work. The revolving drum is designed to make a revolution once in every ten minutes, and with the construction shown, it will be practicable to retard 90 any one of the channelers, put in new tools or make repairs and run it forward to a working position without stopping the 95 drum.

I claim as my invention:—

1. A tunneling machine comprising a car, a central drill spindle, a drill carried thereby, means for operating said spindle, a support rigidly carried by the car and concentric with the drill spindle, said support 100 projecting from the car and engaging the heading, a series of secondary drills, and means for supporting them on the support around the spindle.

2. A tunneling machine comprising a car, 115 a central drill spindle, a drill carried thereby, means for operating the spindle, a support rigidly carried by the car and concentric with the drill spindle, said support being in rear of the drill and having its free 120 end of substantially the same diameter as the drill, whereby said support may enter the hole drilled in the heading, a series of secondary drills, and means for supporting them around said spindle.

3. In a tunneling machine, a centrally arranged drill spindle and means for operating the same, a tube inclosing the same, said tube being adapted to enter a socket formed in the heading by said centrally arranged 130

drill, a series of drills about said tube and spindle and means for radially adjusting said drills.

4. A tunneling machine comprising a car, 5 a centrally arranged drill spindle, a drill carried thereby, means for operating the spindle, a support rigid with the car and concentric with the drill spindle for engaging the heading, a spider concentric with 10 the support and supported thereby, and a series of secondary drills carried by the spider, said drills being radially adjustable on said spider.

5. In a tunneling machine, a car, a tube 15 mounted thereon and projecting forwardly therefrom, a second tube concentric with said first named tube and projecting in advance of the same, a drill spindle within said second named tube, the forward end 20 of said second named tube being adapted to enter the drill hole with said spindle, a drum having anti-friction bearings on said tube, means for revolving said drum and a series of channel cutting drills mounted on 25 said drum.

6. A tunneling apparatus comprising a car, a centrally arranged drill spindle therefor having a drill, and a casing inclosing said spindle and adapted to enter the drill hole therewith, a revolving drum concentric with said spindle, a series of channel cutting drills mounted on said drum and means for operating said drill spindle and drills.

7. A tunneling machine comprising a car, 35 a central drill, a central support rigid with the car and concentric with the drill and adapted to engage the heading, a revolving drum carried by the support, and a series of channelers carried by said drum.

40 8. A tunneling machine comprising a car, a central drill, a central support rigid with the car and concentric with the drill and adapted to engage the heading, a drum mounted on and revolving around said support, said drum being in the form of a truncated cone with its outer end contiguous to the heading, and channelers mounted on said drum.

9. In a tunneling machine, a central support, a revolving drum, a series of screws mounted on the periphery of said drum at intervals, carriages mounted on said screws, drill cylinders having link connections with said carriages, and means for swinging said 55 cylinders toward or from said drum.

10. In a tunneling apparatus, a longitudinally arranged stationary support, a stationary gear thereon, a drum having anti-friction bearings on said support, a series 60 of screws having driving connections with said gear, a series of carriages mounted on said screws and drills carried thereby, and means for revolving said drum.

11. In a tunneling machine, a car, a centrally arranged drill spindle and drill car-

riages supported on the sides of said car and movable back and forth thereon, and drills vertically arranged in said carriages, screw shafts whereon said carriages are movable and driving connections between 70 said screw shafts and said drill spindle.

12. In a tunneling apparatus, a car, a drill spindle mounted thereon projecting forwardly therefrom, and means for driving said spindle, brackets hinged on the sides of 75 said car and adapted to swing back against the walls thereof, means for locking said brackets in a position at right angles substantially to said car, carriages horizontally 80 slideable between said brackets, screw shafts whereon said carriages are movable and driving connections between said screw shafts and said drill spindle.

13. In a machine of the class described the combination of a center drill and means 85 for operating the same, a tube adapted to follow said center drill into the heading, a series of secondary drills, a support for said secondary drills and means for moving said supports radially with respect to said 90 tube, substantially as described.

14. A tunneling machine comprising a centrally arranged spindle, a drill therefor and means for operating the same, a revolving drum having a bearing on said spindle, 95 a series of channelers carried by said drum, carriages wherein said channelers are mounted, and means connecting said carriages with said drum and permitting their movement toward or from said drum.

15. In a drilling machine, a revolving drill carrier, a central support therefor adapted to engage the heading to be drilled, a drill spindle operating within said support, drill carriages mounted on said carrier and revolving around said support and means for radially adjusting said carriages on said carrier.

16. A tunneling machine comprising a car, a central drill spindle having a drill 110 and means for operating the same, a support rigid with the car and concentric with the drill spindle and adapted to engage the heading in rear of the drill, a series of secondary drills, tilting carriages therefor, and 115 means supporting said carriages around said spindle.

17. A tunneling machine comprising a car, a centrally arranged drill spindle having a drill and means for operating the 120 same, a support rigid with the car and concentric with the drill spindle and adapted to engage the heading in rear of the drill, a series of secondary drills, tilting carriages therefor, means supporting said carriages, 125 said carriages being capable of adjustment toward or from said drill spindle.

18. In a tunneling machine comprising a car, a centrally arranged drill spindle, a drill and means for operating the same, a 130

support rigid with the car and concentric with the drill spindle and adapted to engage the heading in rear of the drill, a revolving spider concentric with said spindle, 5 a series of tilting, secondary drills carried by said spider.

19. A tunneling apparatus comprising a revolving drum, a support therefor, reciprocating carriages on the drum, and channelers 10 having parallel link connections with said carriages for radially adjusting the channelers.

20. A tunneling apparatus comprising a car, a revolving carrier supported by said car, a drill spindle located centrally of said 15

carrier, a drill carried by said spindle, means for operating said drill to cut a socket in a tunnel heading, a central support in the rear of said drill for engaging the socket in the tunnel heading in rear of 20 the drill and around which support said carrier revolves; carriages mounted on said carrier, and secondary drills supported by said carriages.

In witness whereof, I have hereunto set 25 my hand this 4th day of August, 1908.

DIGHTON A. ROBINSON.
